CONVEYER MECHANISM

Hans O. Irmscher, East Hempstead, Long Island,
N. Y., assignor to National Urn Bag Co. Inc.,
a corporation of New York

Application November 25, 1943, Serial No. 511,668

2 Claims. (Cl. 214—17)

The present invention relates to filler apparatus for feeding fluent material in manufacturing packages and the like, and more particularly is directed to automatically operated mechanism for delivering or feeding to packaging machines, tea, coffee or the like, in required quantities from a suitable bulk source.

In the manufacture of filled packages, such as tea balls and the like, in large scale production, quantities of tea or other filling material must be intermittently fed to the packaging machine from a bulk supply source while preserving at all times the fluent conditions of the filling material. The present invention provides an improved mechanism to successfully give results of the character described adapted for use in connection with super high-speed packaging machine, such as fully disclosed in applicant's copending application, Serial No. 450,289, filed July 9, 1942, for Infusion package manufacture.

Among the objects of this invention is to provide a mechanism of the character described which shall comprise relatively few and simple parts that are easily assembled and incorporated in the construction of automatic machines for making complete infusion packages, or the like, which shall maintain a supply of filler material in quantity required with certainty and reliability, which shall operate smoothly and be substantially free from vibration, which shall be inexpensive to construct yet capable of supplying the requirement of large capacity super high-speed packaging machines, and shall be practical and efficient to a high degree in use.

Other objects and advantages will be in part obvious and in part hereinafter pointed out.

The invention accordingly consists of features of construction, combination of elements and arrangement of parts which will be exemplified in the construction hereinafter described and of which the scope of the application will be indicated in the following claims. In the accompanying drawings, in which is shown one illustrative embodiment of this invention.

Fig. 1 is a side elevational view of a conveyer supply-filler feed apparatus constructed to embody the invention as applied to a super high-speed infusion package manufacturing machine, only a fragmentary portion of the latter being shown.

Fig. 2 is enlarged cross section view of a fragmentary portion of the improved conveyer mechanism showing an automatic control for the supply filler feed.

Fig. 3 is a cross sectional view taken on line 3—3 in Fig. 2, and

Fig. 4 is a view showing the electrical system, circuit and motor control of the improved conveyer system shown partly diagrammatic.

Referring to the drawings, 10 denotes a super high-speed fully automatic machine for making complete infusion packages, such as tea balls, and the like article, in large scale production. Only 10 a fragmentary portion of said machine 10 is shown in Fig. 1 with the improved conveyer filler apparatus 11 constructed to embody the invention incorporated in the connection with such machine 10. The latter may be of any well known 15 construction, but as here shown is like that shown and described in the copending applications referred to above.

As seen from Figs. 1 and 2, the portion of machine 10 shown has a suitable base frame support

20 10a which may carry on a horizontal top 10b thereof, in the manner fully disclosed in detail in said aforementioned application, means for feeding a web of heat-sealing filter paper W or similar suitable sheet material continuously 25 thereto from a suitable source. Said web W is folded longitudinally as it passes to the machine 10 to form a closed bottom B and open top O. The folded web W is gripped transverse the length thereof between continuously moving pairs 30 of uniformly closely spaced pincer spring pressed jaws 10c of machine 10, the jaws 10c being pivotally mounted for movement toward and away from each other and advanced through the machine 10 by any suitable interconnecting means. 35 The effective opening and closing movement of the pincer jaws 10c are controlled by suitable rollers 10d and cam rails 10e rigidly secured to extend along the machine top 10b.

The business ends of jaws 10c are seen to be 40 fork-shaped to firmly grip the folded web W about the lower ends of spaced chain-linked hollow funnel members or spouts 10f inserted down into the folded web open top O in the successive bag sections M, which extend between the forked portion 45 of the pairs of jaws 10c. Said funnel members 10f by suitable arrangement are caused to be successively entered into and retracted upwardly from the underlying bag section M as they advance through the machine 10.

50 When the bag sections M reach the position in alignment with spaced chutes 20a of a feed measuring mechanism 20, the aligned spouts 10f are then in position under chutes 20a for delivering a charge of tea T or the like infusion material thereto. The feed measuring mechanism 20 may

be of any well known construction, and as here shown may be like that fully described in another of applicant's copending application Serial No. 486,196, filed May 8, 1943, for Filler apparatus for measuring a feed supply in packaging fluent products except as hereinafter pointed out.

The improved feed supply apparatus 11 as constructed and used to embody this invention will now be described.

As shown in Figs. 1 and 2 apparatus 11 may include a hopper 12 of adequate capacity from which a supply of the fluent material, such as tea T, to be packaged in the form of teaballs, is automatically drawn as required for the continuous operation of the machine 10. Said hopper 12 may be positioned just above the level of floor F so as to be convenient for dumping from cases bulk material T therein, said hopper 12 being provided with downwardly tapering side walls to permit the fluent material T to flow by gravity to the bottom 12a thereof.

The hopper bottom 12a may be seated to empty the fluent material T into the inlet of a suitably constructed elevator-conveyer 13 which has a continuous tight fitting casing 13a enclosing chain-driven flights 13b for elevating quantities of the material T passing from the hopper 12 to the discharge end 13c of the conveyer 13 above and into a drop chute 14, as shown in Figs. 1 and 2. Said conveyer flights 13b are driven in the well understood manner, as for example, through a sprocket and chain drive 13d, suitable speed reduction means 13e and electric motor E. Said speed reduction means 13e and motor E, together with an electric starter relay R for the motor E which may be of any well known construction, are mounted on angle cross bars 13f secured to midportions of the conveyer casing 13a.

The drop chute 14, as seen from Figs. 1 and 2 forms a quantity control supply chamber, the bottom of said chamber 14 passing the fluent material T through the measuring mechanism 20 and hence to the chutes 20a.

Starting with the chamber 14 empty, and with a supply of bulk fluent material T dumped into the hopper 12, the motor E which may be connected to a suitable electric power source in the well understood manner may be started for running the conveyer elevator 13 to deliver the fluent material T picked up by the chain-driven flights 13b within casing 13a to the discharge end 13c and hence to the drop chute chamber 14. Should the fluent material T in passing through chamber 14 exceed the quantity being removed by the measuring mechanism 20 and pile up to accumulate to the high level L in the chamber 14, there is provided for limiting further piling up, a diaphragm wall portion 30 in the drop chute forming said chamber 14. Said diaphragm wall portion 30 actuates an electric micro-switch 40 that controls through relay R the electric power circuit for starting and stopping the motor E.

The diaphragm wall portion 30 as seen from Figs. 2 and 3 preferably is installed in a wall section opening 31, of said chamber 14, the plane of which slopes at less than 90° in angular relation to a horizontal plane so that any fluent material T piled up in chamber 14 against the diaphragm wall portion 30 will exert pressure thereagainst the slope of said wall portion 30 preferably being greater than the angle of repose of said fluent material T, that is, about 45°.

Said opening 31 is seen to extend across the entire width of the chamber 14, said diaphragm wall portion 30 being constructed to comprise a pair of

plates 32 between which is secured a flexible fabric or sheet material 33 by suitable means such as screws 34. The fabric sheet material 33 extends beyond the perimeter of said plates 32 and has the edge border portions 33a thereof secured to the rim of chamber wall opening 31 by a frame 35 and screws 36 as shown in Figs. 2 and 3.

The micro-switch 40 may be mounted on a bracket 41 from a relatively fixed wall portion of chamber 14 spaced from the wall portion diaphragm 30, and is provided with rigid arm 40a on which at 40b is pivoted by one end 40c, a lever 40d. The free end of said lever 40d carries an adjustable bolt 40e which contacts the outer surface of the diaphragm wall portion plate 32. A mid-portion of said lever 40d adjacent the pivoted end 40c contacts a pressure push bar 40f which operates the micro-switch 40. Thus by adjusting the bolt 40e any pressure on the diaphragm wall portion 30 due to the piling up of fluent material T in chamber 14 will be transmitted through the push bar 40f to actuate the micro-switch 40 thereby opening the circuit to the motor E and stopping the conveyer and delivery of fluent material T from the bulk supply in the hopper 12 to the chamber 14.

The normal capacity of the delivery of fluent material T by the conveyer is made greater than that required for the measured filling operation by mechanism 20 so that the chamber 14 can be automatically kept from overflowing, the control being constructed and arranged so that the micro-switch 40 cuts off the electric power completely when the pile of fluent material T reaches the high level L and the power is again restored to permit operation of the conveyer 13 when the pile of fluent material T reaches the lower level J, the level of the lowest end of the diaphragm wall portion 30.

It is thus seen that there is provided a mechanism in which the several objects of this invention are achieved and which is well adapted to meet conditions of practical use.

As various possible embodiments might be made of the above invention, and as various changes might be made in the embodiment above set forth, it is to be understood that all matters herein set forth or shown in the accompanying drawings are to be interpreted as illustrative and not in a limiting sense.

Having thus described my invention, I claim as new and desire to secure by Letters Patent:

1. In a filler apparatus of a high speed packaging machine for feeding charges of fluent material to bags from a bulk supply source comprising a chamber from which the charges are drawn spaced from said supply source, means for moving the fluent material from the supply source to the chamber including a motor drive, the chamber having a wall structure formed with a flexible sectional area extending substantially the width of the chamber in an angular relation of less than 90° to a horizontal plane and more than the angle of repose of said material to provide a gravity operated diaphragm, a micro-switch actuated by said diaphragm and connected in circuit with the power operating the motor drive for controlling the accumulations of fluent material in said chamber, including a lever pivoted at one end from a relatively stationary chamber wall portion support having the lever mid-portion adjacent the pivoted end operate the micro-switch, and means adjustable to correspond to deflections of the diaphragm carried by the free end of the lever for contacting the diaphragm whereby grav-

ity pressure of the fluent material accumulated in the chamber exerted on the diaphragm actuates the micro-switch, said flexible sectional area forming the diaphragm being secured to provide a tight closure extending over an opening in said chamber wall structure.

2. In a filler apparatus of a high speed packaging machine having a chamber from which charges of fluent material are drawn spaced from a supply source of such material and an electrical motor driven means for moving the fluent material from the supply source to the chamber, said chamber formed with a deflectable diaphragm wall portion extending substantially the width of the chamber in an angular relation of less than 90° to a horizontal plane and more than the angle of repose of said material to provide a gravity op-

erated diaphragm, micro-switch actuated by movements of said diaphragm and connected in circuit with the power operating the motor driven means for controlling the accumulations of said material at a determined level in the chamber, 5 said diaphragm forming a tight closure extending over an opening in the wall structure of said chamber, a lever pivoted from a relatively stationary portion of the chamber wall structure adjacent said opening and interposed between the micro-switch and the diaphragm, said lever carrying an adjustable means for varying the effective operation of the micro-switch to correspond to predetermined levels of the material accumulated in the chamber.

10 HANS O. IRMSCHER.
